DONAT N. PAQUETTE, OF DRACUT, MASSACHUSETTS, ASSIGNOR TO NEW HOME WASHING MACHINE CO., OF DRACUT, MASSACHUSETTS, A CORPORATION OF MASSACHUSETTS

SET TUB WASHING MACHINE OUTLET AND PACKING BOX

Application filed March 26, 1929. Serial No. 350,082.

This invention relates to devices for washing clothes in the home.

I am aware that there are many kinds of portable clothes washing machines operated by power, and I am aware that there are certain types of dish washing machines which are not portable.

An objection to the portable type of clothes washing machines is that it is difficult to fill them and to empty them. In some cases they can be filled with a hose and in some cases the water can be drained into a pail through an outlet in the bottom, and in other cases different types of suction devices are used for emptying them.

This invention relates to the type of tubs known as set tubs which as ordinarily used are rectangular in shape when viewed from the top, and which are set in position. Such tubs are usually fastened to the wall and as part of their equipment there are hot and cold water faucets, the water from which goes into the tub.

Many tubs have outlets at the rear or in a corner, and some have them at the middle of the bottom.

The purpose of this invention is to provide a power washer associated with a permanently fixed set tub having a water inlet, and an outlet at the center of the bottom for an ordinary plug so that the tub can be used for hand washing if desired, combined with a certain type of outlet through which the power drive shaft operates.

For the purpose of converting this tub into a power washing machine, I provide a special form of packing box which extends down from the central outlet and having preferably in one side a clean out opening and in the other side a waste pipe connection which connects with a waste pipe having a shut off valve. Preferably the handle of this valve extends out near the front under the tub within easy reach of the operator.

I also provide power means which gives to a vertical drive shaft a reciprocating motion. This drive shaft extends up through a water tight bearing and terminates at a point a little below the bottom or floor of

the tub so that the shaft does not interfere with the outlet plug.

I also provide a rotor having any suitable form of blades and a hub which extends down into the tub outlet and engages the end 55 of the drive shaft when it is desired to use the device for power washing.

In the drawings, Fig. 1 is an elevation of a set tub of a well known rectangular or box shaped type viewed from the front and with 60 part of the front wall broken away to show the interior.

Fig. 2 is a plan view of Fig. 1.

Fig. 3 is a vertical sectional view showing a modified construction of the packing box 65 outlet.

Fig. 4 is a small size plan view of a tub which is not rectangular.

Fig. 5 is a vertical sectional view of my preferred type of packing box outlet. 70

In the drawings, A represents a set tub preferably of rectangular form at the bottom 13, and having about the middle of the bottom a flush outlet 14. 1 represents a skirt or splash board which extends up on wall D at 75 the back of the tub and through this project one or more water inlets such as 10 and 11, each provided with a suitable shut off valve.

B represents a drive shaft packing box which extends down from outlet 14 and has 80 at one side a clean out opening 21 into which fits a plug 22 and at another side a waste pipe connection 23.

As shown, packing box B is attached to the bottom of the tub A by means of a thimble 5 85 which extends down snugly through outlet 14 as shown at 15, and which preferably has an annular skirt 16 which extends out into an annular recess 6 surrounding outlet 14.

Thimble 5 is threaded at 17 to engage interior threads 20 in the top of packing box B. 18 is a fastening nut with interior threads 2 which engage threads 17 whereby the floor 13 of the tub is clamped between 16, washer 113 and nut 18. 95

In the bottom of packing box B is a threaded hole 7 into which is screwed the threaded part 24 of shaft bearing 25. 28 is a central hole through bearing 25 through which snugly passes vertically the drive shaft C. 100

26 represents an annular mercury cup which extends around the top of shaft bearing 25, such cup being filled with mercury 27.

The drive shaft C extends up through bearing hole 28 and terminates at the top end 30 which is located below the floor 13 of the tub and, as shown, is formed with a vertical slot 31 to receive a pin 42 in the downwardly projecting hub 41 of a detachable clothes washing rotor K having suitable blades 40.

F represents an annular skirt which is tightly fixed on drive shaft C and extends down at 62 below the mercury level in mercury cup 26. Through the solid top 61 of this skirt is the hole 60 through which shaft C passes, and the joint between 60 and shaft C is preferably air and water tight so as to prevent any liquid from working down to the hole 28 through which shaft C fits with a smooth running fit. Skirt F moves with the shaft C but bearing 25 does not move with it.

The rotor K is shown as having the hub 41 in which is a hole 44 which fits over the end 30 of shaft C and through this passes the pin 42 adapted to engage slot 31.

The means to give the drive shaft a reciprocating motion as shown includes a motor L which may be of the electric type and has a shaft 50 keyed to which is an eccentric 51 around which is an eccentric strap 52 which by means of an arm 53 engages crank arm 33 of shaft C, thus giving it motion. The lower end 34 of shaft C rests on a thrust bearing 4 which, as shown, is fixed to the floor L.

70 is a shut off valve in waste pipe H operable through a shaft 71 and hand wheel 72 near the front and bottom of the tub within easy reach of the operator.

When used as a hand washing device, the rotor K is lifted off and a plug P is put in its place.

161 is a washer which I may use to help keep the shaft water tight.

As shown in Fig. 3, I may use a different type of packing box and a slightly different type of shaft.

80 represents the packing box which extends downward from a central outlet in tub floor 13, and preferably has the clean out 81 and the waste connection 82 with valve 83.

At the bottom 84, I show any kind of elastic packing 86 held in place by the packing nut 85 which is screwed upward into 84 and has a bearing hole 87 through which passes the shaft 89 which terminates in a squared end 88 at a point below the tub bottom 13.

While I prefer to use a set tub with a rectangular floor, I may use a set tub 90 of the shape shown in Fig. 4.

The front of this tub is semi-circular and the back where it is attached to wall 91 is straight. 92 is a water inlet and 93 is a centrally disposed flush outlet from which extends a waste pipe 95 having a shut-off valve

96 which can be operated by a handle 97 proximate the front of the tub.

It is obvious that the rotor might be more or less permanently fixed to the drive shaft if desired. This fixing of the rotor to the drive shaft may occur if, as shown in Fig. 5, the metal of the hole 44 and the metal of the outside of shaft 30 are of steel, iron or other easily rusted material and they rust together or if the fit between these parts is a drive fit instead of a sliding fit.

I claim:

1. The combination with a set tub having a water inlet and a flush outlet at substantially the center of its rectangular bottom; of a drive shaft packing box which extends down from said outlet and has in one side, a clean out opening and at another side a waste pipe connection and at the bottom; a threaded shaft bearing hole; a shaft bearing screwed up into such shaft bearing hole, said bearing having an annular mercury cup around its top; a drive shaft which extends up through the shaft bearing and terminates in a slotted end below the tub bottom; an annular skirt which is fixed to the drive shaft and extends down into the mercury cup; a waste pipe which extends from said packing box connection and has a shut off valve; and a detachable clothes washing rotor having blades and having a hub which extends down below the hub bottom and engages the end of the drive shaft; together with means to give the drive shaft a reciprocating motion.

2. The combination with a set tub having a water inlet and a flush outlet at substantially the center of its rectangular bottom; of a drive shaft packing box which extends down from said outlet and has in one side, a clean out opening and at another side a waste pipe connection and at the bottom, a shaft bearing around the top of which is an annular mercury cup; a drive shaft which extends up through the shaft bearing and terminates in a slotted end below the tub bottom; an annular skirt which is fixed to the drive shaft and extends down into the mercury cup; a waste pipe which extends from said packing box connection and has a shut off valve; and a detachable clothes washing rotor having blades and having a hub which extends down below the tub bottom and engages the end of the drive shaft; together with means to give the drive shaft a reciprocating motion.

3. The combination with a set tub having a water inlet and a flush outlet at substantially the center of its rectangular bottom; of a drive shaft packing box which extends down from said outlet and has in one side, a waste pipe connection and at the bottom, a shaft bearing around the top of which is an annular mercury cup; a drive shaft which extends up through the shaft bearing and terminates below the tub bottom; an annular skirt which is fixed to the drive shaft and extends

- down into the mercury cup; a waste pipe which extends from said packing box connection and has a shut off valve which has a handle proximate the front of the tub; and a
- 5 detachable clothes washing rotor having blades and having a hub which extends down below the tub bottom and engages the end of the drive shaft; together with means to give the drive shaft motion.
- 10 4. The combination with a set tub having a water inlet and a flush outlet at substantially the center of its rectangular bottom; of a drive shaft packing box which extends down from said outlet and has in one side, a
- 15 waste pipe connection and at the bottom, a shaft bearing around the top of which is an annular mercury cup; a drive shaft which extends up through the shaft bearing; an annular skirt which has a solid top the upper
- 20 face of which is substantially level with the bottom of said outlet and is fixed to the drive shaft, the annular skirt portion extending down into the mercury cup; a waste pipe which extends from said packing box con-
- 25 nection and has a shut off valve; and a detachable clothes washing rotor having blades and having a hub which engages the end of the drive shaft; together with means to give the drive shaft motion.
- 30 5. The combination with a set tub having a water inlet and a substantially rectangular bottom which slopes down toward the center and a flush outlet from said center; of a drive shaft packing box which extends down from
- 35 said outlet and has in one side, a waste pipe connection and at the bottom, a shaft bearing around the top of which is an annular mercury cup; a drive shaft which extends up through the shaft bearing to a point below
- 40 the bottom of the tub; an annular skirt having a solid top which is fixed to the drive shaft and which has a top face which is substantially level with the bottom of the waste pipe connection, the annular skirt portion extend-
- 45 ing down into the mercury cup; a waste pipe which extends from said packing box connection and has a shut off valve; and a detachable clothes washing rotor having blades in the top and having a hub which extends down
- 50 therefrom into the outlet and which engages the end of the drive shaft; together with means to give the drive shaft motion.

DONAT N. PAQUETTE.
